ISRAEL FOSTER, OF SAME PLACE.

Design No. 4,181, dated June 28, 1870.

DESIGN FOR A CARPET-PATTERN.

The Schedule referred to in these Letters Patent and making part of the same.

I, WILLIAM KERR, of Philadelphia, county of Philadelphia, State of Pennsylvania, have invented or produced a Design for a Carpet-Pattern, of which the following is a specification.

In the accompanying drawing is represented sufficient of a carpet to illustrate my design, the remainder of the pattern being merely a repetition of that which is shown.

The design consists of the members A and B, and of a foliated ornament, C, composed of flowers, leaves, and stems, as shown, and occupying a portion of the space between the said members.

The central portion of the member A is of the character represented, and the said member has a border, composed of curved lines, *a*, and is surrounded by a wreath, *b*.

The member B has, in the center, an ornament, *f*, and is surrounded by a border composed of curved ribs and foliated and other ornaments, as clearly represented in the drawing.

Irrespective of the colors employed,

I claim—

The design for a carpet-pattern, substantially as described and as represented in and by the accompanying drawing.

In testimony whereof I have signed my name to this specification in the presence of two subscribing witnesses.

WILLIAM KERR.
